CLAIM

The ornamental design for a bucket lid for a low-profile dust collector, as shown and described.

DESCRIPTION

FIG. 1 is a top plan view of the outer shell of a bucket lid for a low profile dust collector according to our new design, with front or intake to the left side, a rear side to the right of this view, a right side thereof at the top of this view, and a left side thereof at the bottom.

FIG. 2 is a left elevational view thereof.

FIG. 3 is a rear elevational view thereof.

FIG. 4 is a right elevational view thereof.

FIG. 5 is a front elevational view thereof.

FIG. 6 is a left rear perspective thereof; and,

FIG. 7 is a front right perspective thereof.

The bottom of the bucket lid forms no part of the claimed design. Flat and curved surfaces are illustrated with solid line surface shading. The dust bucket, on which the bucket lid is mounted, shown in broken line, forms no part of the claimed design. The area inside the intake duct and discharge duct, shown in broken line, forms no part of the design. Other elements that are shown in broken lines do not form a part of our claimed design.

1 Claim, 4 Drawing Sheets
